UNITED STATES PATENT OFFICE.

ADA E. MOORE, OF ST. ANTHONY, IDAHO.

COMBINED ASH CAN AND SIFTER.

1,210,347.

Specification of Letters Patent. Patented Dec. 26, 1916.

Application filed April 4, 1916. Serial No. 88,895.

To all whom it may concern:

Be it known that I, ADA E. MOORE, a citizen of the United States, residing at St. Anthony, in the county of Fremont and 5 State of Idaho, have invented new and useful Improvements in Combined Ash Cans and Sifters, of which the following is a specification.

The invention relates to a combined ash 10 can and sifter.

The primary object of the invention is the provision of a can and sifter of this character wherein an ash or coal receptacle can be placed therein and dumped for the 15 sifting of the contents without the escape of dust from the can, thereby obviating the scattering of dust and dirt during the sifting operation of ashes or coke in the use of the can.

Another object of the invention is the provision of a can of this character wherein the hanger for an ash or coal receptacle is 20 readily adjusted so that different sizes of receptacles can be placed within the can and dumped for discharging its contents 25 into the sifter which, when actuated, will thoroughly sift the ashes, cinders or coal.

A further object of the invention is the provision of an ash can and sifter of this 30 character wherein the construction thereof is novel in form so as to eliminate dust and dirt when in the act of sifting ashes, cinders, coal or the like, and also which is readily operated for the dumping of the 35 contents of the receptacle into the sifter and also for the sifting of said contents.

A further object of the invention is the provision of a can or sifter of this character which is simple in construction, thoroughly 40 reliable and efficient in operation, strong, durable and inexpensive in manufacture.

Other objects will be in part obvious and in part hereinafter set forth.

The invention accordingly consists in the 45 features of construction, combination of elements and arrangement of parts which will be exemplified in the construction herein-after described, and the scope of the application of which will be indicated in the appended claims.

In the accompanying drawings: Figure 1 is a side elevation of a can constructed in accordance with the invention; Fig. 2 is a top plan view thereof, with the cover or lid removed; Fig. 3 is a sectional view on the line 3—3 of Fig. 1, showing by full

lines a receptacle held within the can and by dotted lines the dumping position of said receptacle; Fig. 4 is a sectional view on the line 4—4 of Fig. 1; Fig. 5 is a perspective view of the hanger removed from the can; Fig. 6 is a perspective view of the agitator removed from the sifter; Fig. 7 is a top plan view of the can, with the sifter and hanger removed therefrom.

60 65

Similar reference characters indicate corresponding parts throughout the several views of the drawings.

Referring to the drawings in detail, A designates a cylindrical body constituting 70 the can and B the removable lid or cover which is telescoped upon the body A for the closing thereof, the body A being provided at diametrically opposite points with loop handles 5 to permit the carrying of the can 75 from one point to another and likewise the lid or cover B is provided with a loop handle 6 which permits the convenient placing of the lid or cover upon the body or its removal therefrom.

Mounted on the body A interiorly thereof, spaced from the bottom of the same, are spaced brackets 7 for supporting a sifter 8 formed with a reticulated or foraminous bottom 9, upon which works a ring-like agitator 10 having a threaded eye 11 with which detachably engages the threaded end 12 of an operating handle 13, the same being passed through a suitable opening 14 formed in the side of the sifter 8 and also through 90 a suitable opening 15 formed in the body A, these openings 14 and 15 being in registration with each other to receive the handle 13 which is formed with a looped outer end 16 so that it can be readily reciprocated for 95 the working of the agitator 10 within the sifter 8, whereby the contents of the sifter will be thoroughly sifted during the working of the agitator. On detaching the 100 handle 13 from the eye 11 of the agitator 10 the said handle can be removed from the openings 15 and 16 and also the agitator 10 can be removed from the sifter and, likewise, the sifter 8 removed from the body A of the can so that the can 105 can be dumped for the discharge of its contents.

Formed in the mouth edge of the body A at diametrically opposite points and opening through the said edge are slots 17 for detachably receiving a receptacle hanger or dumper which comprises a frame 18, the 110

straight parallel rods 19 of which have movably fitted thereon slides 20 which are adjustable relative to each other and carry adjustable screws 21 on which are swiveled 5 hook-like clamps 22 adapted to engage the wall of a receptacle containing ashes, cinders, coal or the like for the fastening of the said receptacle upon the frame 18 to permit the dumping thereof for the discharge 10 of its contents into the sifter. The ends of the frame 18 are formed with trunnions 23 which detachably fit in the slots 17 for rotatably mounting the frame in the body A of the can, one of the trunnions 23 being 15 fitted with a ring 24 constituting a handle so that the frame can be rotated for the dumping of the receptacle fastened thereon. On removal of the trunnions 23 from the slots 17 the hanger and dumper can be readily 20 taken from the body A of the can.

The lid or cover B is of a height sufficient to permit the turning of a receptacle by the frame 18 when rotated, so that the contents of the receptacle can be dumped into the 25 sifter 8 within the can, and on operating the agitator 10 in the sifter 8 the said contents will be thoroughly sifted without possibility of the escape of dust or dirt from the can during the sifting operation.

30 The adjustability of the slides 20 on the rods 19 of the frame 18 permits the positioning of the clamps 22 so that the same will engage different sizes of receptacles or 35 pans containing ashes, cinders, coal or the like to be dumped into the sifter when the can is closed.

From the foregoing description, taken in

connection with the accompanying drawings, the construction and manner of operation of the herein described ash can and 40 sifter will be thoroughly understood and, therefore, a more extended explanation has been omitted.

Having thus described my invention, I 45 claim:

1. The combination with a receptacle adapted to be supported in a can, of a supporting frame having spaced parallel side guide rods and trunnions at opposite ends for detachable and rotatable engagement in 50 diametrically opposite points of the can, slides movable on the rods, adjusting screws threaded centrally in the slides, cross pieces swiveled on the adjusting screws, and jaw 55 clamps carried by the cross pieces, each being formed from a relatively stiff wire.

2. The combination with a can having a plurality of brackets interiorly thereof forming a bearing, of a sifter body removably engaged with the bearings and having a foraminous bottom, a ring-like member movable over the bottom, a wire wrapped about the ring-like member and forming a triangle centrally thereof, said ring-like member having a threaded eye, and a lever 60 slidable through the can and sifter and detachably engaged in the threaded end.

In testimony whereof I affix my signature in presence of two witnesses.

ADA E. MOORE.

Witnesses:

W.M. E. DAILY,
ARTHUR ALLEN.
